United States Patent Office

Des. 194,509
Patented Feb. 5, 1963

194,509

DUST PAN

Samuel L. Beder, New York, N.Y.
(3640 Johnson Ave., Riverdale, N.Y.)

Filed Nov. 3, 1961, Ser. No. 67,372

Term of patent 7 years

(Cl. D44—18)

FIG.1

FIG.2

FIG.3

FIG.4

FIG.5

FIG. 1 is a top plan view of a dust pan showing my new design;

FIG. 2 is a bottom plan view;

FIG. 3 is a rear elevational view;

FIG. 4 is a front elevational view; and

FIG. 5 is a side elevational view.

The essential features of my design reside in the portions shown in full lines on the drawing.

I claim:

The ornamental design for a dust pan, substantially as shown and described.
